UNITED STATES PATENT OFFICE.

FRANK C. SOPER, OF CHICAGO, ILLINOIS, ASSIGNOR TO THE LUXFER PRISM PATENTS COMPANY, OF SAME PLACE.

DESIGN FOR A PRISM-LIGHT.

SPECIFICATION forming part of Design No. 27,976, dated December 7, 1897.

Application filed November 1, 1897. Serial No. 657,103. Term of patent 14 years.

To all whom it may concern:

Be it known that I, FRANK C. SOPER, a citizen of the United States, residing at Chicago, in the county of Cook and State of Illinois, have invented a certain new and original Design for Prism-Lights, of which the following is a specification.

My invention relates to designs for prism-lights.

Figure 1 is a plan view of a prism-light embodying my design. Fig. 2 is a section therethrough.

A is the body of the prism-light. B B are prisms on one side thereof. C C are subordinate prisms on the opposite side, arranged

in the form of a pattern, and D D are field-spaces.

The essential features of my design are found in a prism-light comprising a substantially flat and thin body with a series of 20 prisms on one side and a series of prisms on the opposite side arranged so as to form a figure or pattern.

I claim—

A design for a prism-light, substantially 25 as shown and described.

FRANK C. SOPER.
